UNITED STATES PATENT OFFICE.

OSCAR F. GRANT, OF PITTSBURG, PENNSYLVANIA.

FOUNTAIN-PEN.

SPECIFICATION forming part of Letters Patent No. 416,293, dated December 3, 1889.

Application filed February 9, 1889. Serial No. 299,287. (No model.)

To all whom it may concern:

Be it known that I, OSCAR F. GRANT, a citizen of the United States, residing at Pittsburgh, in the county of Allegheny and State 5 of Pennsylvania, have invented certain new and useful Improvements in Fountain-Pens; and I do hereby declare the following to be a full, clear, and exact description of the invention, reference being had to the accompanying drawings, which form part of this specification.

This invention has relation to fountain-pens, and has for its object the provision of a novel construction of point-holder or plug 15 and ink-feeder, whereby a steady and uniform supply of ink to the writing point or nib is insured and the feeder or plug adapted to all ordinary shapes and sizes of writing points or nibs.

20 My invention consists in the novel construction and combination of parts hereinafter described.

In the accompanying drawings, Figure 1 is a vertical central section of a fountain-pen embodying my improvements. Fig. 2 is a perspective view of preferred form of feeder. Fig. 3 is a perspective view of a modified form of feeder. Fig. 4 is a side view of pen complete.

30 In carrying my invention into effect I use any suitable style of holder—such as a hollow stem or tube A, of hard rubber, celluloid, or other material, open at both ends and provided with a soft-rubber ball b or other means 35 for producing suction, so as to fill the tube or fountain A when the lower end is dipped into the ink supply or bottle. In the lower end of the tube A is fitted a plug B, consisting of a short tubular section, which constitutes the 40 support and retaining device for the nib or writing-point which is inserted in the space between the plug and case A. A portion a of the plug projects beyond the end of the case A, and this extension is an important 45 feature, the purpose being to avoid the necessity in filling the holder A of dipping the latter in the ink, as well as to carry the ink down nearer the writing-point than would be possible if the plug were made flush with the 50 end of the holders. This projecting portion of the plug should be hollowed out, as shown

at c, to accommodate the sunken portion of the "Falcon pen," preferred by many writers, and for the use of which in fountain-pens no provision, so far as I am aware, has hitherto 55 been made.

D designates the ink - feeder, which, as shown in Figs. 1 and 2, consists of a strip or rod of hard rubber or other material, of square or rectangular form in cross-section, and of a 60 size to snugly fit the circular hole through the plug B. At its lower end the feeder is cut or bent laterally, as shown at I, and then continued lengthwise in the form of a tapered tongue e in the direction of the point of the 65 pen, against the inner or under surface of which it impinges when in position.

The stem b' of the feeder is of sufficient length to extend some distance up into the reservoir-space of the holder A. The spaces 70 left on the four sides between the feeder and the plug B are to provide channels for the passage of the ink up into the reservoir in filling the latter. They also serve, when the pen is in use, to admit air into the reservoir. 75

The stem of the feeder is split in the direction of its length from the upper end to a point immediately back of the bend or shoulder I, where it intersects at right angles another cut or perforation proceeding in the direction of the bent portion through the latter from the outer extremity of the bend. The tongue e is channeled lengthwise on its upper or outer surface, as indicated at g, and by reason of the taper or wedge-like shape of 85 the tongue this channel extends through the latter at its extremity, dividing the point of the tongue into two and forming a space which will accumulate sufficient ink to cause the pen to write as soon as touched to paper. 90 The intersecting cuts, perforations, and channels through the feeder provide passages for the constant flow of ink from the reservoir to the writing-point; but as they are very narrow and small at points of intersection they 95 prevent the too rapid flow of the ink, and only furnish a supply according as the channel in the tongue of the feeder becomes exhausted.

In making and adapting the feeder to the plug its stem is first split in the direction of its length, and the two halves are spread apart and set to remain so. When the feeder is in-

serted in the plug, the two halves spring apart and hold the feeder in place by pressure against the walls of the plug.

The stem of the feeder is made longer than the plug for two reasons—first, to admit of the feeder being adjusted to suit different lengths of pens, and, second, so as to extend sufficiently far up into the ink-reservoir to reach the main body of the ink in case the ink should be suspended in the fountain by reason of adhesion to the sides above the plug.

It will be observed that my improvement contemplates a novel construction and arrangement of parts wherein the writing point or nib is entirely independent of the feeder, and that while any style, size, or shape of pen may be used it may be removed and replaced with facility and without disturbing either the plug or the feeder.

In other fountain-pens using ordinary detachable nibs the writing-pen has either been attached to or held in place by the feeder or by some supplementary device, which either prevents the pen from being detached independently or renders the feeder a permanent fixture incapable of removal or adjustment. In my pen the feeder is readily adjustable or entirely removable without disturbing the pen, and can therefore be lengthened or shortened to suit long or short pens. Again, the writing-pen in my improvement is in the most convenient position for use, being fitted outside the plug and entirely above or outside the feeder; hence there can be no danger of the ink encroaching on the holder or on such parts of the writing-point as would cause it to blot, spill, or soil the fingers.

While I have described above one special form of feeder, I may use other forms—as, for instance, that shown in Fig. 3, wherein a hole is bored through the otherwise solid stem and meets the slit cut through the bend.

A variety of feeders within the spirit of my invention are susceptible of use in connection with the tubular plug and independent writing-nib, and need not be specially described.

Having described my invention, what I claim as new, and desire to secure by Letters Patent, is—

1. In a fountain-pen, the combination, with a tubular reservoir or fountain-holder, of a tubular plug fitting inside the end of the holder and a detachable feeder fitting within said plug and extending into the reservoir, said plug and holder being constructed and arranged, substantially as described, so as to admit between them the writing-nib, as set forth.

2. In a fountain-pen, the combination, with a tubular reservoir or fountain-holder, of a hollow plug having a plain exterior surface fitting the end of the holder and a feeder fitting within and detachable from said plug, a space being provided between the plug and holder for the reception of the writing-point, substantially as set forth.

3. In a fountain-pen, the combination, with the tubular holder forming a fountain or reservoir and the hollow plug constituting a holder or clamp for the writing-point, of the feeder consisting of the rod D, having the bend d and channeled tapering tongue e, said rod being split in the direction of its length, and said bend cut toward and at right angles with said split and intersecting the same, substantially as set forth.

In testimony that I claim the foregoing I have hereunto set my hand this 26th day of January, 1889.

O. F. GRANT.
